United States Patent Office.

JAMES B. WHEEDEN, OF BALTIMORE, MARYLAND.

Letters Patent No. 92,239, dated July 6, 1869.

IMPROVED WINDOW-AWNING.

The Schedule referred to in these Letters Patent and making part of the same.

To all whom it may concern:

Be it known that I, JAMES B. WHEEDEN, of city and county of Baltimore, and State of Maryland, have invented a new and useful Improvement in Window-Awnings; and I do hereby declare the following to be a full, clear, and exact description of the same, sufficient to enable others skilled in the art to which my invention appertains, to make and use the same, reference being had to the accompanying drawing, forming part of this specification, and in which the figure is a perspective view of an awning from the inside of a building, showing my invention applied.

My invention relates to that class of awnings which, at their lower edges, are attached to a bent rod, or metallic frame hung to the building. Heretofore, the inner edges of awnings of this class have been made fast to the window or door-frame, by means of a cord attached directly to the canvas, to hold the awning down, and prevent the sides of the same from being blown about by the wind. It was necessary to unloose these cords before the awning-frame could be raised to a closed position, and on this account many have objected to the awning as being too troublesome. Some have tried to secure the edges of the canvas by tacking the same to the frame of the door or window. It was found, however, that when an attempt was made to raise the awning, the tacks were drawn out, one by one, or the canvas torn away, beginning with the lowest attachment and ascending.

The object of the present invention is to do away with this cord-attachment; and

It consists in the employment of slides, fitted on the side-bars of the awning-frame, and connected by means of cords, made permanently fast to the window or door-frame, said slides having connection with the sides of the awning, near the inner edges of the same, so that the awning can be raised and lowered without loosening the cords, the slides moving on the bars of the frame for this purpose, and at the same time retaining the canvas in proper shape.

My invention will be fully understood by reference to the following detail description of the accompanying drawings.

In the drawings—

A may represent a window or door-frame, and B C, the ordinary frame of an awning of this description, hung to the frame A, so as to be raised and lowered by means of a cord, D.

The canvas or awning proper is attached in any suitable manner at the top, to or above the door or window-frame.

E are the slides, fitted on the side-bars B B, of the awning-frame. These slides may be made of a single piece of wire, bent as shown, or they may be cast, or even made of wood, as found best adapted, on account of cheapness and other considerations, by the manufacturer. There is a connection at one or more points between the slides and the sides of the canvas or awning, near the inner edge of the latter.

a are cords, or other suitable connections, made fast at one end to the slide, and at the other, to the door or window-frame.

It will be seen, that when the operating-cord is drawn upon, the awning-frame will be raised, and as this continues, the slides will move outward on the side-bars of the frame, permitting the folding of the awning, without loosing the attachments, and without straining and injuring the canvas at the points of connection with the slides.

By the use of this invention, the awning is always kept in proper shape, and can be immediately raised, in cases of sudden storm or gusts of wind, by means of the operating-cord.

Having thus described my invention,

What I claim as new, and desire to secure by Letters Patent, is—

The combination of the awning and frames B C, slides E, and cords D a, in the manner substantially as specified.

To the above specification of my invention I have signed my name, this 10th day of June, 1869, in the presence of two subscribing witnesses.

JAMES B. WHEEDEN.
